UNITED STATES PATENT OFFICE.

WILBUR J. WATSON, OF EAST CLEVELAND, OHIO, ASSIGNOR OF ONE-HALF TO EDWARD M. GRAVES, OF CLEVELAND, OHIO.

BULKHEAD CONSTRUCTION.

Application filed May 20, 1922. Serial No. 562,292.

To all whom it may concern:

Be it known that I, WILBUR J. WATSON, a citizen of the United States, residing at East Cleveland, in the county of Cuyahoga and State of Ohio, have invented a certain new and useful Improvement in Bulkhead Constructions, of which the following is a full, clear, and exact description.

This invention relates to a construction of bulkheads for use particularly in marine works, such as wharves, docks, levees, jetties, breakwaters and the like.

My invention has for its object the attaining of the greatest possible strength and safety in such structures with the greatest possible economy in the cost of materials and of erection.

More particularly, it is the object of this invention to provide a relatively light wall constructed of sheet piling which is capable of withstanding heavy pressure.

Further objects will appear from the following description and the annexed drawing.

Generally speaking, the invention may be said to comprise the elements and combinations thereof set forth in the accompanying drawings.

In the annexed drawing, Fig. 1 is a horizontal section through the upper portion of the wall; Fig. 2 is a section similar to Fig. 1 showing a slightly modified construction; Fig. 3 is a vertical section on line 3—3 of Fig. 1; Fig. 4 is a section on line 4—4 of Fig. 1; Fig. 5 is a detail view showing the piling interlock.

Referring to the annexed drawings, the bulkhead consists of a corrugated wall 1 formed by a zigzag row of piling driven into the ground and braced as will be hereinafter described. The piling forming the body of the wall preferably consists of sheet piles 1^a interlocking edge to edge arranged in a zigzag row and driven a suitable distance into the ground. The zigzag wall 1 formed by the piling 1^a has regularly spaced outturned and inturned portions forming vertically extending corrugations. The inner peaks 2 and the outer peaks 3 of the corrugations are in substantial alignment. In order to rigidly brace the corrugated wall structure, a reinforced concrete cap beam 4 of a width substantially corresponding to the depth of the corrugations in the wall is secured upon the top of the piling.

The cap beam 4 has inner and outer depending edge flanges 5 and 5^a which, respectively, connect the peaks 2 and 3 of the corrugations on opposite sides of the wall. Likewise the cap beam 4 has depending diagonal ribs 6 in which the upper edge of the piling 1 is imbedded. The ends of the diagonal ribs 6 are enlarged as shown at 6^a where they join the side flanges 5 and 5^a and the peak portions of the corrugations are imbedded in the thickened portions 6^a.

The cap beam 4 also has depending transverse ribs 8 extending at right angles to the edge flanges 5 and 5^a from the middle of the thickened portion 6^a on one side to the opposite edge flanges. The flanges 5, 5^a and ribs 6 preferably extend to the water line and protect the upper edge portion of the piling which would otherwise be exposed. It is not essential that the reinforcing cap beam be of concrete, since if desired a composite structural steel beam corresponding to the concrete beam shown may be used. It is not essential that the piling be of the same length since it may be advisable to provide longer piles extending further into the ground in some parts of the wall, depending upon the load to be supported and the character of the ground into which the piles are driven.

In Fig. 2 of the drawing, a slightly modified construction is shown in which the corrugations of the wall formed by the sheet piling 11 are triangular in shape. The inner and outer peaks 12 and 13 of the corrugations being in alignment as in the modification previously described so that the corrugations are of uniform depth.

In the modified construction illustrated in Fig. 2 a cap similar to that shown in Figs. 1 and 3 is employed. This cap beam 14 has depending edge flanges 15 connecting the peaks 12 on the inner side of the wall and the peaks 13 of the corrugations on the outer side of the wall. Diagonal ribs 16 are formed on the inner side of the cap beam and the upper edge of the piling 11 is imbedded in these ribs. Thickened blocks 17 integral with the edge flanges 15 and diagonal ribs 16 are formed at the intersections between the edge flanges 15 and diagonal ribs 16. The peak portions 12 and 13 of the corrugations are imbedded in the blocks 17. The cap beam is also provided with transverse ribs 18 at right angles to the edge

flanges 15 and extending from the blocks 17 in which the peak portions of the corrugations are imbedded directly across to the opposite edge flange 15.

5. In both modifications above described, the cap beam provides an effective reinforcement for the wall. The edge flanges of the cap beam provide rigid braces between the peaks of adjacent corrugations on the inner 10 and outer sides of the wall respectively. The diagonal ribs rigidly hold the upper edge of the wall to shape and strengthen the inwardly and outwardly extending portions of the wall and the transverse intermediate 15 ribs form braces between the peak of each corrugation and the edge flange on the opposite side of the beam and add materially to the rigidity of the structure. An embankment 19 may be filled in beyond the wall and 20 beneath the cap beam if desired.

Having described my invention, I claim:

1. A bulkhead, comprising a wall formed of sheet piling driven into the ground, said 25 piling having interlocking edges adapted to transmit stresses horizontally in the direction of the sheeting, said wall having a continuous curvature and turned inwardly and outwardly at regular intervals lengthwise thereof, to form vertical corrugations and 30 bracing means connecting the peaks of adjacent corrugations at the front and rear of the wall, respectively.

2. A bulkhead, comprising piles driven 35 into the ground in a row with regularly spaced inwardly and outwardly turned portions forming a corrugated wall, and a cap beam, of a uniform width substantially corresponding to the depth of the corrugations, secured upon the upper edge of the wall.

- 40 3. A bulkhead, comprising sheet piling interlocked edge to edge and driven into the ground, said piling being arranged in a row with regularly spaced inwardly and outwardly turned portions forming a corrugated wall, and a cap beam, of a uniform 45 width substantially corresponding to the depth of the corrugations, secured upon the upper edge of the wall.

4. A bulkhead, comprising sheet piling interlocked edge to edge and driven into the 50 ground, said piling being arranged in a row with regularly spaced inwardly and outwardly turned portions forming a corrugated wall, and a concrete cap beam of uniform width within which the upper edge 55 of the piling is imbedded with the peaks of the corrugations adjacent opposite edges of the beam.

5. A bulkhead, comprising sheet piling interlocked edge to edge and driven into the 60 ground in a row having regularly spaced inwardly and outwardly turned portions forming a corrugated wall, and a cap beam having depending flanges connecting the 65 peaks of the corrugations on opposite sides of the wall and transverse stiffening ribs connecting said flanges.

6. A bulkhead, comprising sheet piling interlocked edge to edge and driven into the 70 ground, said piling being arranged in a zigzag row with regularly spaced inwardly and outwardly turned portions forming a corrugated wall, and a concrete cap beam upon the upper edge of said corrugated wall, 75 said cap beam having depending edge flanges connecting the peaks of the corrugations on opposite sides of the wall and transverse stiffening ribs extending from the peak of each corrugation to the rib on the 80 opposite side of the beam.

7. In a bulkhead, the combination with a wall formed of sheet piling interlocked edge to edge and arranged with regularly spaced inturned and outturned portions forming vertical corrugations, of a concrete cap beam of a width corresponding substantially to the depth of the corrugations, said cap beam having depending longitudinal ribs at the edges thereof, diagonal ribs in which the upper edge of the piling is embedded, and transverse ribs extending directly across the beam from the peak of each corrugation to the flange on the opposite side of the beam.

In testimony whereof, I hereunto affix my signature.

WILBUR J. WATSON.
